UNITED STATES PATENT OFFICE.

ALFRED R. MORRILL, OF SWAMPSMOTT, MASSACHUSETTS, ASSIGNOR TO UNITED SHOE MACHINERY CORPORATION, OF PATERSON, NEW JERSEY, A CORPORATION OF NEW JERSEY.

INSEAM SEWING-MACHINE.

1,350,377.

Specification of Letters Patent. Patented Aug. 24, 1920.

Application filed February 26, 1918. Serial No. 219,313.

To all whom it may concern:

Be it known that I, ALFRED R. MORRILL, a citizen of the United States, residing at Swampscott, in the county of Essex and State of Massachusetts, have invented certain new and useful Improvements in Inseam Sewing-Machines; and I do hereby declare the following to be a full, clear, and exact description of the invention, such as will enable others skilled in the art to which it appertains to make and use the same.

The invention relates to inseam sewing machines, and its object is to improve the operation of the back gage, or the combined back gage and welt guide of such machines, so that it will press the work snugly against the channel guide and the upper snugly into the shoulder of the insole, without striking objectionable blows upon the work.

To this end the back gage is brought up to and gradually pressed against the work under spring pressure, preparatory to the entrance of the needle into the work, and is thereafter positively advanced to finally compress the work and hold it during the retraction of the needle and the tightening of the stitch. To insure a gradual application of the yielding or spring pressure to the work, the gage is preferably brought up to a fixed preliminary position, and is then gradually forced forward against the work. The full force of the spring pressure is thus gradually applied, after which the work is further compressed or squeezed to a definite degree by the positive advance of the gage.

The features of the invention outlined above, as well as further features referred to in the claims, will be understood from an inspection of the accompanying drawing and the following detailed description of the mechanism illustrated therein.

In the drawings, Figure 1 is a side elevation showing so much of a sewing machine as is necessary to illustrate the application of the present invention thereto; Fig. 2 is a detail side elevation on a somewhat larger scale; Fig. 3 is an end view looking toward the left in Fig. 2; and Fig. 4 is a detail showing the links connecting the back gage or welt guide carrier with its operating slide.

In the drawings the invention is shown as embodied in an inseam sewing machine having the general construction and mode of

operation of the machine shown and described in Patents Nos. 1,076,201, October 2, 55 1913, and 1,108,560, August 25, 1914. This machine is provided with a curved hook needle 2, a looper 4, a thread arm 6, a channel guide 8, a back rest 10, and a back gage 12, which in the machine shown is also a welt 60 guide. The back gage or welt guide is secured on the end of a carrier lever 14 which is connected to a slide 16 corresponding to the back gage or welt guide slide of the patents above referred to. This slide is uniformly retracted at a given point in each cycle of the machine by a cam actuated lever 18, the lower end of which is connected by a link 20 with a clutch box 22. The slide is pressed forward by a spring 24 70 which engages a pin 26 projecting from the side of the slide. The forward movement of the slide is controlled by the cam lever until the slide is released by the clutch box and is free to move forward under the influence of the spring 24. The forward position of the slide when released is determined by the engagement of the back gage with the work, or by the stop nut 28, which is adjusted on a rod projecting from the rear 75 end of the slide. The slide is locked against backward movement while the needle is being retracted by a locking roll 30 which is operated by the cam lever 32 as fully explained in Patent No. 1,108,560.

The back gage is brought up to a fixed position by the above mechanism, and is then gradually forced forward toward the channel guide by a supplemental mechanism which continues the forward movement of the gage after the back gage slide is arrested, and after it is locked. This mechanism comprises two links 34 and 36 connecting the back gage carrier 14 with the forward end of its operating slide 16, and a bell 90 crank lever 38, the horizontal arm of which is provided with a slot 40 engaged by the pivot pin 42 which connects the links. The vertical arm of the bell crank lever is connected with the lower end of a cam operated lever 44 by a link 46, the end of which is connected to a pivot block adjustably mounted in a slot in the arm.

To secure the best results, the stop nut 28 should be so adjusted that the forward 105 movement of the back gage, under the in-

fluence of the spring 24, will be arrested by the stop before the gage strikes the shoe, thus avoiding the hammering action of the back gage which might otherwise occur.

- 5 During this forward movement of the back gage into its preliminary position, the bell crank lever 38 is in such position that the slot 40 is parallel to the slide 16, and the advance movement of the slide has no effect 10 upon the pivotal connection between the links 34 and 36. After the back gage has been brought into preliminary position, the bell crank lever is rocked to gradually straighten the toggle formed by the links 15 34 and 36. The back gage will thus be gradually forced against the shoe, and will apply a yielding pressure which is supported by the spring 24. The movement of the bell crank lever tending to straighten 20 the toggle continues after the needle has entered the work, and after the slide 16 has been locked against backward movement. After the slide is locked, the continued straightening of the toggle will force the 25 gage forward positively a definite amount, thereby giving the work a predetermined positive squeeze or compression which is maintained or continued during the retraction of the needle, and which presses and 30 holds the upper snugly in the shoulder of the insole and the shoe firmly against the channel guide. In sewing certain classes of work the thickness of the materials between the channel guide and the back gage may be so much 35 greater about the toe than along the sides of the shoe that the back gage will strike the work in sewing about the toe before the stop, if set for the proper operation along the sides of the shoe, will arrest the forward 40 movement of the back gage slide. In such case the pivot pin between the toggle links will be nearer the fulcrum of the bell crank lever at the time the positive squeeze takes place, thereby reducing the squeeze to better suit the conditions along this part of the 45 shoe.

While it is preferred to use the construction and arrangement of parts shown and described, in embodying the invention in 50 the machine of the patents above referred to, it will be understood that this construction and arrangement is not essential to the broader features of the invention, but may be varied or modified as found desirable or best suited to the construction and arrangement of the parts in the machine to which the invention is to be applied.

Having explained the nature and object 60 of the invention, and specifically described one form of mechanism in which it may be embodied, what is claimed is:—

1. An inseam sewing machine, having, in combination, a needle, a channel guide, a back gage, and mechanism for forcing the 65 back gage against the work under spring

pressure prior to the penetration of the work by the needle and for positively advancing the gage during the retraction of the needle.

2. An inseam sewing machine, having, in 70 combination, a needle, a channel guide, a back gage, mechanism for advancing the gage to a predetermined position, mechanism for giving the gage a supplemental forward movement under spring pressure to 75 force it gradually against the work and for giving it a final positive movement to compress the work between the gage and channel guide.

3. An inseam sewing machine, having, in 80 combination, a needle, a channel guide, a back gage, mechanism for advancing the gage under spring pressure, a stop to arrest said advance, and supplemental mechanism for gradually forcing the gage forward 85 against the work after it is arrested by the stop.

4. An inseam sewing machine, having, in combination, a needle, a channel guide, a back gage, mechanism for advancing the 90 gage under spring pressure, a stop for arresting said advance, and supplemental mechanism for gradually and positively forcing the gage forward against the work 95 after it is arrested by the stop.

5. An inseam sewing machine, having, in combination, a needle, a channel guide, a back gage, mechanism for uniformly retracting the gage, a spring for advancing the gage, a stop for limiting said advance, and 100 mechanism for continuing the advance of the gage to force it against the work and for imparting a final positive movement thereto.

6. An inseam sewing machine, having, in 105 combination, a needle, a channel guide, a back gage, a back gage slide, mechanism for retracting the slide, a spring for advancing the slide, a stop for limiting the forward movement of the slide, mechanism for locking the slide, and means acting against the 110 resistance offered by the slide for forcing the gage toward the channel guide.

7. An inseam sewing machine, having, in 115 combination, a needle, a channel guide, a back gage, a back gage slide, mechanism for retracting the slide, a spring for advancing the slide, a stop for limiting the forward movement of the slide, mechanism for locking the slide, and means acting against the 120 resistance offered by the slide for forcing the gage toward the channel guide before and after the slide is locked.

8. An inseam sewing machine, having, in 125 combination, a needle, a channel guide, a back gage, a back gage slide, connections between the slide and back gage through which motion is transmitted to the back gage, mechanism for retracting the slide, a spring for advancing the slide, a stop for deter- 130

mining the forward position of the slide, mechanism for locking the slide, and mechanism for actuating the connections between the slide and gage to force the gage gradually toward the channel guide.

5 9. An inseam sewing machine, having, in combination, a needle, a channel guide, a

back gage, a back gage slide, mechanism for retracting and advancing the slide, a slide lock, a toggle connecting the slide and gage, 10 and mechanism for actuating the toggle after the slide has been advanced.

ALFRED R. MORRILL.
